UNITED STATES PATENT OFFICE.

JOHN B. KENNY, OF GENEVA, NEW YORK.

LEAD-PENCIL.

No. 889,932.

Specification of Letters Patent.

Patented June 9, 1908.

Application filed January 27, 1908. Serial No. 412,885.

To all whom it may concern:

Be it known that I, JOHN B. KENNY, a citizen of the United States, resident of Geneva, in the county of Ontario and State 5 of New York, have made a certain new and useful Invention in Lead-Pencils; and I declare the following to be a full, clear, and exact description of the same, such as will enable others skilled in the art to which it 10 appertains to make and use the invention, reference being had to the accompanying drawings, and to letters or figures of reference marked thereon, which form a part of this specification.

15 Figure 1 is a central longitudinal section of the invention as applied. Fig. 2 is a similar view showing the rubber tip almost entirely exposed. Fig. 3 is a similar view showing the rubber tip entirely inclosed. Fig. 4 is a 20 side view of the invention as applied. Fig. 5 is a central longitudinal section of a modified form of the invention.

The invention has relation to lead pencils 25 provided with tips of rubber or other erasing material, and has for its object the provision of means in connection with such a tip whereby it may be entirely used in erasing and whereby it may be protected when not in use.

30 Other objects and advantages will herein-after appear.

In the accompanying drawings, illustrating the invention, the letter *a*, designates a lead pencil and *b*, its rubber tip which is 35 secured to the end of the pencil in the usual manner.

c, is a short sleeve of thin metal which is secured upon the end portion of the pencil a short distance from its termination, in any 40 suitable manner, the space between the end of the pencil and the sleeve being marked *c'*. This sleeve is provided with an external screw thread *c*², running throughout its length, and fitting thereover in engagement 45 therewith is a longer internally threaded sleeve *d*, also of thin metal and having at its outer end an inward extending annular flange *e*, provided with a short sleeve extension *f*, of the same diameter as the short 50 sleeve *c*, and capable of close engagement with the rubber tip, whose external diameter is the same as the internal diameter of the

sleeve extension. The thread of the sleeve *d*, extends from its inner end to the inward extending flange thereof, and the length of 55 the short sleeve extension is the same or about the same as the length of the interval *c'*, between the end of the pencil and the short sleeve *c*.

In the use of the device, the rubber tip is 60 normally protected or entirely inclosed at its sides, as shown in Fig. 3 of the drawings. As the rubber or erasing material is used, the outer or longer sleeve *d*, is gradually turned down upon the pencil until the sleeve extension *f*, thereof will lie in the interval *c'*, between the end of the pencil and the short sleeve *c*, as shown in Fig. 2; when the last remaining portion of the erasing material may be employed. At the same time the 70 short sleeve extension *f*, will always have close bracing engagement with the rubber tip.

In Fig. 5 of the drawings is shown a modified form of the invention wherein the inner 75 sleeve *x*, is made longer and is of rotary character, being confined at each end by bands *y*, *y*, fixed upon the pencil. In this form of the device the movement of the outer sleeve for the purpose already described is effected 80 by turning the inner sleeve by means of the thin knurled or milled flange *z*, at the lower end thereof. The device is otherwise the same as in the main form of the invention.

Having described the invention, what I 85 claim and desire to secure by Letters Patent is:

1. The combination with a lead pencil having a rubber tip, of an inner fixed sleeve provided throughout its length with an external 90 screw thread, an outer internally threaded adjustable sleeve having engagement with said inner sleeve, and provided at its outer end with an annular inward extending flange having a bracing cylindrical sleeve extension 95 of an internal diameter which is the same as the diameter of the rubber tip and capable of close bracing engagement with said tip.

2. The combination with a lead pencil having a rubber tip, of an inner sleeve separated from the end of the pencil by an interval, and provided throughout its length with an internal screw thread, an outer externally threaded sleeve having engagement with 100

said inner sleeve and provided at its outer end with an annular inward extending flange having a short sleeve extension of the same diameter as the inner sleeve, capable of close engagement with the rubber tip, and of being withdrawn into said interval at the end of the pencil.

In testimony whereof I affix my signature, in presence of two witnesses.

JOHN B. KENNY.

Witnesses:

Wm. J. HUNT,
MARGARET DESMOND.
